Attorney.

UNITED STATES PATENT OFFICE

BERNARD E. JONES, OF MONESSEN, PENNSYLVANIA

GAME

Application filed October 7, 1930. Serial No. 486,946.

My invention relates to games, and more particularly to game boards for use in simulating baseball games.

One object of my invention is to provide a game board for playing games similar to baseball and the like, in the playing of which the element of skill does not enter, but wherein all players have an equal chance to win.

10 Another object of my invention is to provide a game of the type referred to wherein there can be no conflicting "plays" and wherein in each play will create a particular situation which cannot involve any complications in 15 the way of apparently conflicting situations of a previous play or plays.

A further object of my invention is to provide a game board particularly suitable for the simulation of baseball, and which will 20 embody a maximum of elements of the conventional outdoor baseball game.

Still another object of my invention is to provide a game board that is simple, inexpensive of manufacture, and which is durable 25 and convenient of operation.

In the accompanying drawings, Figure 1 is a face or plan view of a game board; Fig. 2 is a view thereof, partially in side elevation and partially in section, and Fig. 3 is an end 30 elevational view thereof.

The game elements proper are mounted upon a base 4 that may be of wood or other suitable material and of a convenient size for handling. Upon the base 4 a playing field 35 is defined by rails 5 which serve as marginal stops or a fence for confining the ball to the playing field and for directing the ball in various angular directions upon contact thereof with the rails.

40 The base when in use is supported in an inclined position by a strut member 6 that is hinged thereto at 7, and may be swung from its folded position of Figs. 2 and 3 to a position at right angles to the plane of the base, 45 so that the rear edge of the base will be higher than the front edge thereof. The front edge of the base is supported upon legs 8.

The playing field of the board, which lies between the rails 5 that have the appearance 50 of a fence which further enhances the simi-

larity to a baseball diamond, contains a series of pins 9 arranged in rows. The pins of each row are offset or staggered with relation to the pins of adjacent rows, so that a ball 10 which is introduced at the entrance opening 55 11 will be directed in zig-zag paths until it reaches a series of aligned rows of pins 12 that form pockets which are designated by "plays" such as "strike", "ball", "three base hit", etc.

A stop bar 13 is hinged to the lower edge of 60 the board so that it can be swung into position on top of the board as shown by dotted lines in Fig. 2, to temporarily retain the ball in the pocket 12 and give the players an opportunity to definitely note which pocket the 65 ball entered. The bar 13 is of trough-like form and inclined toward a receptacle 14, so that when the bar 13 is swung to the position shown in Fig. 1, the ball will roll from the 70 pockets 12 into the cup 14 from which it can be readily removed and again placed into play at the opening 11.

The upper portions of the rails 5 are of irregular form so that when the ball engages certain portions thereof it will be deflected 75 toward the mid portion of the field at different angles than when it engages other portions thereof, thus adding to the uncertainty and interest of the game.

A score board 15 contains insignia for balls, 80 strikes and outs, and pointers 16, 17 and 18 are pivotally mounted on the base 5 for indicating these plays. A baseball diamond 19 is imprinted or otherwise applied to the base 4 and contains pivoted pointers 20, 21 85 and 22, for showing which, if any, of the bases are theoretically occupied by runners.

In playing the game, if the ball 10 enters that pocket 12 which indicates that the batter has made a single, the imaginary batter 90 of course becomes a runner, and the pointer 20 is turned to show that he is on first base. If on the next roll of the ball a two-base hit is indicated at the point where the ball comes to rest between the pins 12, the pointer 22 will 95 be turned to indicate that the previous batter has advanced to third base, while the pointer 21 will be turned to indicate the second batter as having reached second base. In case a single is indicated by the second play, the pre- 100

vious batter would of course advance only to second base. In other words, runners are only advanced a distance determined by the base hits.

5 In case the ball comes to rest in the pocket marked "grounded-out" the batter will be thrown out at first base and runners on the bases will be advanced.

For example, if we already have a runner 10 on first base, and the batter grounds out, the runner who is on first base goes to the second base and the batter is out. If the next batter grounds out, the batter is out and the runner on second base does not advance. If the first 15 batter of an inning hits a three base hit he of course becomes a runner on third base with no one out. If the next two batters ground out he still remains on third base, as the fielder is supposed to hold the runner on the 20 base while throwing out the batter. If the bases are full with no one out and the next batter grounds out, the runner on third base scores, but if the next batter grounds out, the runner on third does not score as first base is 25 unoccupied.

The hit batsman becomes a runner on first base, and if a runner was already on first base, that runner advances to second base. If runners were on first and second bases they advance one to make room at first base for the hit batsman. If runners are on first base and third base, and batter becomes a hit batsman, the runner on first base goes to second base, but the runner on third base does not advance.

30 35 A runner does not advance on the play "Flied Out".

"Safe Bunt" is the same as a single, advancing a runner one base regardless as to what base he is on.

40 "Three strikes" constitutes an out, and four balls puts the batter on first base, and if a runner is already on first base that runner advances to second base.

Two persons are to play, each person to represent a side.

Three outs retire one side.

Nine innings constitute a full game and the side having the most runs at the end of nine innings wins the game.

50 I claim as my invention:—

1. A game board comprising a base having a playing field defined by rails, deflecting pins on said field, receiving pockets disposed across the forward edge of the field, the board 55 being inclined upwardly and rearwardly from said forward edge, and a stop bar pivotally mounted at the lower side of said pockets to release the balls therefrom, the stop bar having a ball-receiving channel that is inclined toward one edge of the board.

2. A game board comprising a base having a playing field defined by rails, deflecting pins on said field, receiving pockets disposed across the forward edge of the field, the board 60 being inclined upwardly and rearwardly 65

from said forward edge, a stop bar pivotally mounted at the lower side of said pockets to release the balls therefrom, the stop bar having a ball-receiving channel that is inclined toward one edge of the board, and a receptacle disposed in position to receive a ball discharged from said channel.

In testimony whereof I, the said BERNARD E. JONES have hereunto set my hand.
